UNITED STATES PATENT OFFICE.

PETER WELIN, OF WORCESTER, MASSACHUSETTS, ASSIGNOR, BY MESNE ASSIGNMENTS,
TO LAWRENCE MAXWELL, OF CINCINNATI, OHIO.

COMBINATION GRAND PIANO.

1,120,775.

Specification of Letters Patent.

Patented Dec. 15, 1914.

Application filed July 6, 1908. Serial No. 441,953.

To all whom it may concern:

Be it known that I, PETER WELIN, a citizen of the United States, residing at Worcester, in the county of Worcester and State of Massachusetts, have invented a new and useful Combination Grand Piano, of which the following is a specification.

This invention relates to combination and automatic musical instruments and more particularly to pianos of the horizontal or "grand" type.

Among the objects of the invention are to so arrange and house the automatic playing mechanism within the casing that the instrument, when closed up or being played manually, has the appearance of an ordinary horizontal or "grand" piano; to provide a series of detachable elements, each of which contains an entire controlling train for one note; to provide for independently securing each striking pneumatic and its controlling valves to the horizontal main wind trunk in a "grand" instrument; to provide means whereby the two foot pedals may conveniently be set so that each actuates the bellows for automatic playing and so that they will serve respectively as "loud" and "soft" pedals for manual playing, and to simultaneously render the bellows inoperative, as by connecting it with the atmosphere; to provide means in an instrument of this style, for allowing the finger keys to remain stationary during automatic playing; to provide an improved way of dividing the action, so that the parts may be conveniently located in a "grand" instrument casing, and so that sections of the entire range of automatically operated notes may be separately controlled for loud and soft effects; to provide an improved arrangement of tracker connections especially suitable for a "grand" piano; to provide means in addition to the ordinary "tempo" controlling means for the motor, for admitting the full effect of the wind to the motor during the playing or forward movement of the music sheet; and in general to provide an improved, efficient, and simple construction of combination "grand" piano to carry out the purposes mentioned herein.

Further objects and advantages will appear hereinafter.

Reference is to be had to the accompa-

nying drawings which show one form in which the invention may be carried out, in which,

Figure 1 is a side sectional elevation of the instrument, the section being taken upon the line I--I of Fig. 2; Fig. 2 is a bottom plan viewed in the direction of the arrow II, Fig. 1, with the striking connections omitted; Fig. 3 is a plan of the key bed and other parts beneath the key-frame with the cover removed, viewed in the direction of the arrow III, Fig. 1; Fig. 4 is a sectional elevation, taken on the line IV--IV of Fig. 3, the controlling levers being omitted; Fig. 5 is a plan of the "key-bed," with its top panels removed; Fig. 6 is a plan of said panels; Fig. 7 is a plan of a frame arranged upon said panels; Fig. 8 is a vertical section through the "divided-action" box, on the line 8--8 of Fig. 2; Fig. 9 is a plan of said box; Fig. 10 is a sectional plan taken just above the bottom board of said box; Fig. 11 is a side central sectional elevation of one of the note operating pneumatics; Fig. 12 is a plan of Fig. 11; Figs. 13 and 14 are plan and cross-section respectively of one of the regulations or "choker" boxes; Fig. 15 is a diagrammatic representation of the general connection, and Fig. 16 is a sectional view on an enlarged scale of certain details shown in Fig. 1.

The instrument, in the form in which it is illustrated in the drawings, is provided with a main Bellows and with a reservoir constantly communicating therewith by means of an open channel or passage. Two chambers or compartments, one for base and the other for treble, are arranged in a convenient manner to be contained within the casing of a "grand" piano, and provided with valves so that they may be put into open communication with the bellows, whereby the whole range of notes of the instrument may be played with loud effect. When it is desired to soften the whole range of notes a valve is operated so that the two chambers or compartments are cut off from open communication with the bellows and communicate therewith only through a choker or pressure regulating device. The regulation of the pressure may be adjusted in any convenient manner. When the choker valve controls the whole range of notes for soft playing, either half of the

notes may be temporarily accented by operating a valve to put either the treble or base chamber or compartment into open communication with the reservoir.

- 5 The motor may be controlled by the tempo valve to put the suction bellows in communication with it so as to drive the motor forward at a steady speed, which is regulated by the tempo valve as is well understood. In addition to this, means is provided whereby in addition to this control of the motor further control is provided so as to produce an accelerated speed. This is accomplished by providing the tempo valve with means whereby, on its continued motion after it entirely opens the tempo valve passage, it comes into contact with another valve which opens a passage or channel to place the suction bellows in open communication with the motor.

In order to reverse the motor for rewinding as rapidly as possible and to simultaneously cut off all communication between the note operating pneumatics and the suction bellows and reservoir, so that no notes may be sounded, the rewinding valve is operated and simultaneously a cut-off valve is moved by the same operation. The latter operates to cut off open communication between the suction bellows and the chambers or compartments above mentioned. The above general description of the operation of the device may be better understood by reference to Fig. 15.

- 35 The construction shown in the drawings will now be described, reference being had first to Figs. 1, 2, 3 and 4. The main wind trunk 2 is arranged across the piano between the transverse braces 3 and 4 and is divided by a wall 5 into two compartments 6 and 7, the compartment 6 being arranged partly on the right and partly on the left of the compartment 7. The right and left hand portions of the compartment 6 are constantly connected by a channel 8. The striking pneumatics 9 with their valve casing 10 are attached to the bottom of the trunk 2, being spaced so that as many as possible can be connected by rods 11 directly to corresponding bell-crank levers 12. Since there is not sufficient room to arrange every pneumatic 9 substantially in line with the note it is to control some are connected by their rods 11 to levers 13 which actuate rocking rods 14 to each of which is connected a secondary lever 440 in line with the desired note.

60 In the example illustrated sixty-five notes are adapted to be automatically controlled by the pneumatics arranged beneath the compartment 7, and the treble half by those arranged beneath the compartment 6. It will be observed that part of the compartment 6 is arranged at the "base" side of the piano to economize space so that there

will be sufficient room for all the pneumatics. Otherwise there would not be enough room on the treble side owing to the shape of the casing 15 (see Fig. 2). The pneumatics arranged beneath the "base" side of the compartment 6 operate the notes through transverse rocking rods 14 as above described.

The "key-bed" 16 is provided on its lower face with a recess which receives the framing of the exhausting bellows 17 two of such bellows being employed, one arranged on each side of the center line of the piano as shown clearly in Fig. 2. The ordinary air exit holes in the bellows are here shown in full, the spring covering plate being omitted. These bellows are actuated by foot pedals 18 each of which is connected through a rod 19 to a plate 20 on the movable member of the bellows, a universal joint 21 of any suitable form being used to allow for the radial movements imparted to the ends of the rod 19. The upper end of each rod 19 is connected with the universal joint through an intermediate member 22 provided with a collar 220 between which and the enlarged end of the rod 19 is a space 23 for the reception of a forked lever 24 or 25. The forked levers 24, and 25, are mounted upon rock shafts 26 and 27 carried in suitable bearings upon manually operated controlling levers 28 and 29 respectively. These latter levers are pivoted at 30 to the "key-bed" 16 and are moved by downwardly projecting finger pieces 31. By moving the levers 28 and 29 toward one another from the position shown in Fig. 2 the forked ends of the levers 24 and 25 are thrown into engagement with the members 22 whereby the actuation of the right hand bellows pedal 18 will rock the shaft 26, and the left hand bellows pedal 18, the shaft 27.

Upon the shaft 27 is mounted a member 32 which may be adapted to control, in any ordinary or convenient manner, the softening mechanism which is not shown herein as it is not a part of this invention, and any form such as usually employed in manually operated pianos of the horizontal or "grand" type may be used.

Similarly the shaft 27 has mounted thereon a member 33 which may be adapted for controlling the mechanism for producing loud effects when playing manually. The latter mechanism preferably consists of any convenient means (not shown) for engaging a pivoted bar 34 (see Fig. 1) which controls the damper rods 35 in the usual way. It will thus be seen that, with the levers 28 and 29 in the position shown in Fig. 2 the foot pedals actuate only the bellows 17 and this will be the position when playing automatically. When playing manually however, the levers are moved toward one another and the two foot pedals will act in the ordinary way as "loud" and "soft" pedals. Since, in the

latter case, the bellows 17 will be operated by the pedals 18, means is provided for rendering the bellows inactive as exhausting bellows. Such means is shown in the form of a hole 36 for each bellows in the key-bed over each lever and adapted to be uncovered when the levers are moved toward each other. This admits air freely to the interior of the bellows 17 through passages hereinafter 15 more particularly described.

The "key-bed" 16 is provided with a number of central compartments or spaces hereinafter described which are covered by panels 37 above which is a frame 38 having further 20 spaces. A cover 39 to the frame 38, together with a block 40, supports the key frame 41. When playing manually the keys 42 actuate the piano action, which is arranged in the space between the front brace 3 and the front 25 of the casing, through loose reciprocating pins 44 which lift auxiliary levers 45 which carry the usual back checks 450 for checking the hammers on their return, and capstan screws 451 for engaging and operating the 30 piano action. These levers 45 are pivoted to a stationary frame 46 supported by bolts 460 secured into the key frame. The keys can be lifted off the key pins and taken out 35 without disturbing the rest of the mechanism. When playing automatically the piano action is actuated through the bell crank levers 12 and loose pins 47 which operate the auxiliary levers 45, the keys 42 remaining stationary. The iron frame 48 for 40 the strings and the sounding board 49 are shown as arranged in their usual positions.

The winding rolls for the perforated music sheet and the upper front portions of the casing may be arranged in any known 45 or convenient way, but it is desirable to arrange them above the key-board substantially as set forth in the specification accompanying my prior application for patent on a combination "grand" piano, Serial No. 495,560 filed April 6, 1908.

Referring now more particularly to Figs. 3, 4, 5 and 6, holes 50 are shown passing through the bottom of the "key-bed" and connecting the bellows 17 with the chambers 51 or spaces 52. These spaces are connected by openings 53 in the panels 37 with the space 54 in the frame 38.

It is to be understood that the "key-bed" 16, as well as other parts of the piano, are 55 usually built up from any number of suitable parts for convenience of manufacture and in this connection it is to be noted that the boards or members forming the central part of the "key-bed" 16 are separated by 60 gaps 55, to allow for expansion and contraction, such gaps being covered with strips of leather or other suitable material pasted thereon to prevent leakage of air.

The space 54 communicates through holes 65 56 in the central panel 37 with channels 57

in the "key-bed" leading to the openings 36. This provides for putting the bellows 17 in communication with one another and for opening them to the atmosphere as hereinbefore mentioned when the openings 36 are uncovered. 70

The connections between the bellows 17 and the main reservoir 58 will now be described. The main reservoir is in the form of a bellows shown at the rear of the instrument (see Figs. 1 and 2). It communicates with a chamber 59 formed in an extension of the casing of the main wind-trunk 2 and separated therefrom by a wall 60. The chamber 59 is in communication through 80 holes 61 with a chamber 62, and this chamber communicates at its outer end with a passage 63 (see Figs. 1, 2 and 8). The latter passage communicates by means of a suitably connected rubber or like tube 630, 85 with a hole 64 in side panel 37, which leads into a space 65 in the "key-bed" 16. Holes 66 in said panel 37 lead into a space 67 in the frame 38 which further communicates downwardly, through holes 68 in the next 90 panel 37, with the space 52 in communication with the bellows 17 as hereinbefore described.

The connections between the main wind trunk compartments or chambers 6 and 7 95 and the bellows 17 (and consequently the reservoir 58 through the connection just described) will next be described. The compartment or chamber 6 communicates through a passage 69 (see particularly Fig. 10: 2 and 8) with a chamber 70 formed in the "divided-action" box. The chamber 70 communicates through a port 71, controlled by a valve 72, with a chamber 73 which extends from this port toward the left hand side of 105 the instrument. Similarly the compartment chamber 7 communicates through a neck 74 (Fig. 2) with a chamber 75 and thence with the chamber 73 through a port 76 controlled by a valve 77. At its left hand 110 end the chamber 73 communicates with a passage 78, which, by any suitable form of connection, communicates with a rubber or like tube as 780, the opposite end of which tube is also suitably connected to an opening 79 in the end panel 37 (see particularly 115 Fig. 3). The opening 79 leads into a space 80 in the "key-bed" 16 which also communicates through a hole 81 in the panel with a space 82 in the framing 38. An opening 83 120 in the panel connects the space 82 with a chamber 84 on the "key-bed" such opening 83 being controlled by a valve 85. The chamber 84 communicates by holes 86, in the panel with a chamber 87 in the framing 38. 125 A hole 88 in the panel 37 is controlled by a valve 89 and connects the chamber 87 with the chamber 52 which is directly connected to the bellows 17 as hereinbefore described.

When the valve 85 covers the opening 83 it 130

uncovers an opening 90, in the left-hand panel 37, which leads to a space 91 in the "key-bed" and thence through a hole 92 in a bottom panel 93 thereof to choker or pressure-regulating device (see particularly Figs. 13 and 14) adapted to operate in any known or convenient manner. The interior of the "choker" device communicates through a hole 94, controlled by an adjustably tensioned valve 95, with the chamber 65 which communicates with bellows 17 through connections hereinbefore described. By moving either of the valves 72 or 77 so as to cover the ports 71 or 76 the ports 96 or 97 respectively are uncovered and placed in communication with the main wind trunk chamber 6 or 7. Ports 96 and 97 in the "divided-action" box lead into a common chamber 98 and thence through a passage 99 to the chamber 59 (see particularly Fig. 1) in the extension of the wind trunk casing, the chamber 59 being in communication with the reservoir 58 as hereinbefore described.

Means will now be described by which the valves 72 and 77 may be controlled pneumatically by finger valves from the front of the instrument. The valves are shown as operated by pneumatics 100 mounted upon the "divided-action box" as shown in Fig. 8, such pneumatics being normally open to the outside air through passages 101 and 102. By admitting air beneath either of two diaphragms 103 the corresponding valve 104 is raised to cut off the atmospheric air from the pneumatic 100 and place it in communication with the passage 98 (under suction) through ports 105 and 106 (see Fig. 10). Air is admitted to the diaphragm controlling the valve 77 in the following manner:—The depression of the front end of a lever 107 (see Fig. 3) pivoted at 108 admits air to an opening 109 and channel 110 in the "key-bed" and thence to an opening 111 in a plate 112. In order to clear the gap 55, a bridge piece 113 is employed (see particularly Figs. 3 and 4). A pipe 213, leads from the opening 111 to an opening 114 in a plate 115 on the main wind trunk 2 (Fig. 2) such opening 114 communicating with passages 116 in the casing of the main wind trunk, and thus conveying the air through channels or passages 117 and 118 to the corresponding diaphragm 103. Similarly the depression of the front end of lever 119 admits air to channels 120, 121, 122 (at the rear of the channel 117) and 123 to the diaphragm 103 which controls the valve 72. Springs 124 return the levers 107 and 119 to their normal positions upon release thereof.

The connections between the bellows and the motor which drives the music sheet will next be described. The chamber 51, in communication with the bellows 17 and reservoir 58 as before mentioned, communicates through openings 125 in one of the panels 37 and a chamber 126 in the frame 38 and thence through holes 127 in the end panel 37, with a chamber 128 in the "key-bed" 16. This chamber 128 communicates through a hole 129, controlled by a valve 130, with a chamber 131 in the frame 38, and thence by way of a hole 132 in the panel and a passage 133 in the "key-bed", with an opening 134, leading through the panel. The latter opening is connected by suitable pipe 234 or the like with the motor for driving the same by suction in a manner well understood. The chamber 128 also communicates through a hole 135 in a bottom panel, 80 of the "key-bed", with a "choker" box or pressure-regulating device 136, which may be similar to the one shown in Figs. 3 and 14. A hole 137 also, of course, in the bottom panel, connects the "choker" box to a passage 138 in the "key-bed", such passage communicating with the aforesaid chamber 131 through an opening 139 in panel 37. This opening 139 tapers, as shown clearly in Fig. 6, and is controlled by a valve 140. When the valve 140 is moved so as to entirely uncover the opening 139 it engages the front edge of a hinged valve 141 (shown in plan in Fig. 3 and in elevation in Fig. 15). This edge is sloped as at 142, whereby the valve 141 is raised by further movement of the valve 140 and opens direct communication between the chamber 131 and the bellows 17 through a passage 143 passing through the "key-bed" 16 and its top and bottom panels. The valve 130, known as the "rewind" valve is operated by the "rewind" lever 144 from the front of the instrument through connections such as shown in Fig. 3. Similarly valve 140, known as the "tempo" valve, is controlled by the "tempo" lever 145 and the valve 85 known as the "choker" valve is controlled by the "choker" lever 146. The outer ends of these levers are adjacent to each other.

The construction of the individual elements containing the note operating pneumatics and their valves which form an important feature of this invention will now be described. The valve box 10 which is shown in Figs. 11 and 12 consists of a number of rectangular sections in which the following passages are formed:—a passage 148 leading to a space 149 communicating with the lower side of a diaphragm 150; a passage 151 leading to the top of the diaphragm 150 and also to a chamber 152 in which is located a diaphragm 153; a passage 155 leading to the pneumatic 9 and adapted to be placed, by valve 154, either in communication with the chamber 152 or with the atmosphere through a passage 156; and a passage 157 connecting the lower side of the diaphragm 153, and with the chamber 158 adapted to be placed by valve 159, either in

communication with the passage 151 or with the atmosphere. The passage 148 is connected with a tube 248 leading to the corresponding hole in the tracker bar, and when air is admitted thereto, the diaphragm 150 is raised thereby raising the valve 159 and admitting air to the chamber 158 and passage 157 to the underside of the diaphragm 153. Valve 154 is thereby raised thus cutting off communication between the atmosphere and the pneumatic 9 and placing it in communication with the chamber 152, and passage 151. The box 10 may be held up to the easing of the main wind trunk 2 by wires passing through holes 160. The passage 151 is placed opposite openings 161 in the main wind trunk whereby the passage 151 is continually under suction. The passage 148 extends through the main wind trunk as shown in Fig. 1. The sections of the box 10 are preferably kept in correct register by pegs 162. The pneumatic 9 is also preferably connected to the valve box 10 in the following improved manner. A hole 163 leading from the pneumatic to the chamber 155 is provided with a vertical extension 164 just wide enough to take a screw 165 adapted to secure the pneumatic to the box 10. The pneumatic 9 may be placed in position upon, or removed from, the box 10 by sliding it on or off the screw 165, and a pin or screw 166 may be provided to prevent lateral movement.

The pipes 267 from the tracker 367 are preferably led first to a collecting plate 167, (see Fig. 2) from which the distributing pipes 248 are led to the openings 148.

The legs of the instrument are attached in any suitable manner, as, for example, by blocks 168, shown in Figs. 1, 2 4, such blocks being hollowed out where necessary for the reception of parts of the "choker" boxes.

The bendings 169 which support the pedal carrying brackets 170 also serve to hide the lower portion of the bellows 17 where the same projects below the "key-bed" 16.

The general operation and control of the instrument will now be described, reference being had to the drawings generally but more particularly to the diagram of connections shown in Fig. 15 whereina the same reference numbers are used to indicate corresponding parts. When the valves 72, 77, 85 and 89 are in the positions illustrated in the drawings, both compartments or chambers 6 and 7 are in open communication with the bellows 17 (and consequently with the reservoir 58 since the latter is always in communication with bellows 17) whereby the whole range of notes of the instrument is being played with loud effect. This open communication takes place from chamber 6 through chambers and passages 69, 70, 71, 73, 78, 79, 80, 81, 82, 83, 84, 86, 87, 88, 52 and 50. The communication from chamber 7 takes place through 74, 75, 76, 73 and from thence through the same as indicated above. When it is desired to soften the whole range of notes of the instrument the choker lever 146 is operated so as to move the valve 85 into a position covering the hole 83 and uncovering the hole 90 whereby the chambers 6 and 7, which are still in communication with the chamber 82 as before, are cut off from open communication with the bellows and only communicate therewith through the choker or pressure-regulating device by means of the following chambers and passages from the chamber 82:—90, 91, 92, 94, 65, 66, 67, 68, 52 and 50. The regulated pressure may be adjusted, as desired, by the adjustment of the spring of the choker device, such adjustment being accomplished in any convenient manner. A spring 171 returns the valve 85 upon release of the lever 146 to its normal position covering the hole 90 and uncovering the hole 83. When the choker valve 85 is operated to control the whole range of notes of the instrument for soft playing, either half of the notes may be temporarily accented by the operation of the levers 107 or 119. Thus by depressing the lever 119 the valve 72 is moved by the collapsing of its pneumatic 100 to cover the port 71 and place the port 96 in communication with the passage 69 and chamber 6, and since the port 96 is in open communication with the reservoir 58 through 98, 99, 59 and 61, the treble note 100 pneumatics connected to the chamber 6 will be accented. Similarly by depressing the lever 107 the valve 77 will be moved and place the chamber 7 in open communication with the reservoir 58 through 74, 75, 97, 98, 99, 105 59 and 61, thereby accentuating the bass notes.

The motor is controlled in the following manner: When the valves 130 and 140, are in the positions shown in Fig. 3, the motor 110 will be stationary. By operating the "tempo" lever 145 so as to move the valve 140 and uncover the port 139 as indicated in Fig. 15, the suction bellows are placed in communication with the motor through the 115 following chambers and passages:—50, 51, 125, 126, 127, 128, 135, "choker-box" 136, 137, 138, 139, 131, 132, 133, 134, and suitable pipe. With this arrangement the motor is driven forward at a steady speed such 120 speed being regulated, as desired, by the adjustment of the "tempo" valve 140, over the tapered port 139 as well understood.

An important feature of the present apparatus lies in means whereby, in addition 125 to the control of the motor when running forward as above described, further control is provided whereby a further accelerated speed may be obtained. To accomplish this the "tempo" lever is moved over until the 130

valve 140 engages and opens the hinged valve 141, as before described, and thereby places the suction bellows in open communication with the motor through the following passages:—143, 131, 132, 133, 134 and the pipe.

When the motor is reversed so as to rewind the music sheet it is desirable to accomplish this as rapidly as possible and it is also necessary, at the same time, to cut off all communication between the note operating pneumatics and the suction bellows and reservoir so that no notes are sounded. This is accomplished in the following manner:—The valve 130 is operated by the "rewind" lever 144 to uncover the hole 129 and, simultaneously, the "cut off" valve 89 is moved to cover the hole 88, such simultaneous movement being arranged for by connecting the two valves together by rods 172 (see Fig. 3). The uncovering of the hole 129 places the suction bellows in open communication with the motor through the following chambers and passages: 50, 51, 125, 126, 127, 128, 129, 131, 132, 133, 134, and the pipe. The covering of the hole 88 cuts off communication between the chamber 87 and 52 and therefore the open or direct path between the bellows 17 and the chambers 6 and 7. It will be understood that at this time the alternative paths of communication between the chambers 6 and 7 and the suction bellows 17 and 58 are all closed since the valves 85, 72 and 77 will be in their normal positions covering the ports 90, 96 and 97, respectively.

Although in the apparatus described the "divided-action" viz. the separate control of different sections of the notes, has been arranged for a division into bass and treble, it is to be understood that other divisions into two or more sections may be arranged for if desired. Further, the control of the valves 77 and 72, may, if desired, be accomplished by any desired means, as hand levers directly connected thereto, instead of by pneumatically actuated mechanism such as described, although the latter is preferable.

While I have illustrated and described the invention as especially applicable to a "grand" piano and while many features thereof are designed solely for that purpose in order to utilize the particular form of "grand" piano casing for housing various parts of the automatic mechanism so as to conceal them, yet some features of the invention are applicable as well to other forms of musical instruments and I am also aware that the invention may be carried out in many other forms and varied in many ways by any person skilled in the art without departing from the scope of the invention as expressed in the claims. Therefore, I do not wish to be limited to the particular de-

tails of construction shown and described, but—

What I do claim is:—

1. In an automatic musical instrument, the combination with a horizontal casing 70 of the grand type, of a key-bed, manual keys mounted over the key-bed, striking connections for said keys, pneumatic operating devices within the casing behind said key-bed, vertical levers arranged at the rear 75 of the keys and key-bed, and horizontal connections in said casing, between said pneumatic operating devices and striking connections.

2. In an automatic musical instrument, 80 the combination of a horizontal pumping bellows having a movable lower leaf and a fixed upper leaf, a key-bed below which said bellows is fixed, means for operating said bellows a member detachably connected thereto for controlling the expression, and a lever for controlling the connection of said member with the bellows operating means.

3. In an automatic musical instrument, 90 the combination of a pumping bellows, pedal connections therefor, a forked lever, a swinging lever on which the forked lever is mounted by which it is moved into and out of connection with the bellows, and 95 means whereby when the lever is in position to make said connection, the bellows will be connected with the outer air and thus rendered inoperative.

4. In an automatic musical instrument, 100 the combination with a pumping bellows, a detachable connection thereto comprising a forked lever, a swinging lever on which the forked lever is mounted, and a channel adapted to be opened by the throw of the 105 swinging lever to a position in which the forked lever is connected with the bellows, said channel communicating with the interior of the bellows.

5. In an automatic musical instrument, 110 the combination of a bellows, a swinging lever, a channel communicating with the bellows and normally closed by said lever, a rock shaft mounted on the lever, an arm 115 on the rock shaft adapted to operate with the bellows when the lever is moved to a position to uncover said channel, whereby the bellows will be rendered inoperative, and a second arm on the rock shaft having a soft playing controller thereon.

6. An automatic piano of the horizontal or "grand" type having a horizontal main wind-trunk therein, note sounding pneumatics and controlling valves, each of said pneumatics with its controlling valves being independently and removably secured to the main wind-trunk in vertical position within the body of the casing of the instrument, and means located in the casing and connected with said note sounding 125 130

pneumatics for operating the striking devices of the instrument independently of the manual keys.

7. In an automatic piano, the combination of a horizontal or "grand" casing having a horizontal main wind-trunk in the rear part thereof, note sounding pneumatics secured to the bottom of said wind-trunk and communicating with the interior thereof, striking connections arranged in front of the main wind-trunk, and substantially horizontal rods extending along the bottom of the casing below the main wind-trunk and connecting said pneumatics with said striking connections.

8. In an automatic musical instrument, the combination of a horizontal main wind-trunk divided into bass and treble sections, one of which extends around three sides of the other, and striking pneumatics vertically arranged on the bottom of said main wind-trunk and communicating with the interior thereof.

9. The combination with a horizontal main wind-trunk, of a valve box removably secured on the bottom thereof, and having a headed pin projecting from one of its vertical sides, and a striking pneumatic having a slot for receiving said pin by which said pneumatic is removably mounted on the side of the valve box, said pneumatic and valve box having communicating passages.

10. The combination with a horizontal main wind-trunk, of a valve box removably secured on the bottom thereof and having a headed pin projecting from one of its vertical sides, a striking pneumatic having a slot for receiving said pin by which said pneumatic is removably mounted on the side of the valve box, said pneumatic and valve box having communicating passages, and a pin for entering the pneumatic and valve box to hold the pneumatic in fixed position on the valve box.

11. In a pneumatic musical instrument, the combination of a main wind-trunk having a treble and bass section, a passage communicating with both of said sections of the main wind-trunk, valves for controlling the communication of said passage with the two sections of the wind-trunk, a pumping bellows and an independent valve-controlled passage between the two sections of the wind-trunk and the pumping bellows.

12. In a pneumatic musical instrument, the combination of a main wind-trunk having a treble and bass section, a pumping

bellows, a passage communicating with both of said sections of the main wind-trunk, 60 valves for controlling the communication of said passage with the two sections of the wind-trunk, an independent valve controlled passage between the two sections of the wind-trunk and the pumping bellows, and a 65 choker valve for controlling the latter passage.

13. In a pneumatic musical instrument the combination of a main wind-trunk having a bass and treble section, a pumping 70 bellows in open communication with both of said sections, a choker valve controlling the connection of the bellows with both of the said sections, a passage, adapted to be opened by the choker valve when it closes 75 the communication between the bellows and the sections for additionally connecting the main wind-trunk with the bellows and a regulating valve in said passage.

14. In a pneumatic musical instrument, 80 the combination of a main wind-trunk having a bass and treble section, a pumping bellows in open communication with both of said sections, a choker valve controlling the connection of the bellows with both of 85 the said sections, a passage, adapted to be opened by the choker valve when it closes the communication between the bellows for additionally connecting the main wind-trunk with the bellows, a regulating valve 90 in the passage, additional individual passages for connecting the bellows with the two sections of the main wind-trunk and individual valves for controlling said last named passages, whereby when the whole 95 instrument is under regulative control, either section of the main wind-trunk may be accented by connecting it directly with the bellows.

15. In an automatic grand piano, the 100 combination of a casing, keys located in the front of said casing, pneumatic devices located substantially on a level with the keys in the rear of said casing, a lever pivoted above the rear part of each key, and means 105 extending forwardly from the pneumatic devices whereby the action of the pneumatic devices will lift the corresponding levers independently of the keys.

In testimony whereof I have hereunto set 110 my hand, in the presence of two subscribing witnesses.

PETER WELIN.
